UNITED STATES PATENT OFFICE.

HOWARD E. NAY, OF WHEELING, WEST VIRGINIA.

DESIGN FOR A PLAQUE-MOUNTING FOR MILITARY HELMETS.

53,930.

Specification for Design.

Patented Oct. 7, 1919.

Application filed March 13, 1919. Serial No. 282,518. Term of patent 7 years.

To all whom it may concern:

Be it known that I, HOWARD E. NAY, a citizen of the United States of America, and resident of Wheeling, county of Ohio, and State of West Virginia, have invented a new, original, and ornamental Design for a Plaque-Mounting for Military Helmets, of which the following is a specification, reference being had to the accompanying drawings, in which—

Figure 1 is a front elevation of a plaque mounting for military helmets, embodying my new design, and

Fig. 2 is a perspective view of the same.
I claim:

The ornamental design for a plaque mounting for military helmets, as shown.

In testimony whereof I have affixed my signature in the presence of two subscribing witnesses.

HOWARD E. NAY.

Witnesses:

H. E. DUNLAP,
A. L. DUNLAP.
